To William C. Paige,
Montgomery.

UNITED STATES PATENT OFFICE

JOSEPH WILLIAM WINTER, OF PENFIELD, PENNSYLVANIA, ASSIGNOR TO MASTER DOMESTIC REFRIGERATING COMPANY, INC., OF CONSHOHOCKEN, PENNSYLVANIA, A CORPORATION OF NEW YORK

REFRIGERATING APPARATUS

Application filed November 13, 1928. Serial No. 319,051.

My invention relates to such apparatus of the automatically operative absorption type. Such apparatus includes a gas generator wherein a refrigerant, such as an aqueous solution of ammonia or similar liquefiable fluid, is intermittently heated to generate ammonia gas from the solution, and cooled, conveniently by a stream of water, to permit the residual solvent to reabsorb said gas; a condenser to which said gas is conducted from said generator, and in which it is condensed while heat is absorbed therefrom, conveniently by a stream of water; and an evaporator to which the condensed refrigerant is conducted, and which is located in the refrigerator inclosure which is to be cooled and from which heat is absorbed by the refrigerant during its expansion to a gaseous state, by such heat. The refrigerant gas from said evaporator is conducted back to the generator, in which it is reabsorbed by the residual water, which has been cooled, and from which it is regenerated by heating said generator, to again pass thru the cycle of changes aforesaid.

My invention is particularly applicable to such apparatus wherein the source of heat is a gas burner, and includes automatically operative means for opening and closing valves controlling both the supply of fuel gas to the burner and the supply of cooling water to the condenser and generator, so as to automatically control the operation of the apparatus.

In the form of my invention hereinafter described, the movements of the valves are effected in one direction by the pressure of fluid in the apparatus and in the opposite direction by springs; and the controlling devices include not only a water valve and a gas valve, which are automatically actuated during the normal operation of the apparatus, but also a gas valve which is a safety device actuated by abnormal high pressure of the fluid in the apparatus to totally shut off the fuel gas supply.

My invention includes the various novel features of construction and arrangement hereinafter more definitely specified.

In said drawings; Fig. I is a diagrammatic, partly sectional, front elevation of

refrigerating apparatus embodying my invention.

Fig. II is a diagrammatic, partly sectional, elevation of the left hand side of said apparatus as shown in Fig. I.

Fig. III is a diagrammatic front elevation of the automatically operative gas and water valve control mechanism shown in the lower part of Fig. I, but in a different position.

Fig. IV is a diagrammatic front elevation of the automatically operative safety gas valve control mechanism shown in the lower part of Fig. I, but in a different position.

In said figures, 1 is a refrigerator cabinet, conveniently formed of double walls with insulating material between them, and inclosing the food compartment 2 and the apparatus compartments 3, 4, and 5. Said compartment 3 is at the base of the cabinet, in communication with the compartment 4 which extends upwardly at the left hand side of said cabinet and in communication with the compartment 5 at the top thereof.

The generator 7, which is in said compartment 3, is a metal cylinder supported in the insulating casing 8 with a flue space 9 around it, in communication with the combustion chamber 10 at the bottom thereof and the flue 11 at the top thereof; which flue extends to the top of the cabinet. The gas burner 12 extends in said combustion chamber 10 and is supplied with gas thru the conduit 13 under control of the working valve 14 and the safety valve 15; which valves are respectively independently automatically controlled as hereinafter described.

Said generator 7, which is charged with an aqueous solution of ammonia as herein-after described, is connected by the conduit 17 with the condensing elements of the apparatus, including the rectifier 18, the conduit 19, and the condenser coil 20. Said condenser coil 20 is connected by the conduit 21 with the evaporating elements of the apparatus, including the manifold 22 and the refrigerating coil 23 which is pendent therefrom in the brine tank 24 which is the heat absorbing element in the food compartment 2. Said coil 23 has the conduit 26 extend-

ing from the lower portion thereof to the top of the water trap 27 which is connected by the conduit 28 with the top of the generator 7.

5 The refrigerating system aforesaid is adapted to be charged with the aqueous solution of ammonia, or other fluid refrigerant, thru the charging valve 30, shown in Fig. II, in connection with said conduit 28.

10 After the charging operation; said conduit 28 is normally closed by the manually operative valve 31, to normally prevent flow of the fluid from said water trap to said generator 7, altho, at intervals, if and when the

15 solvent water accumulates in said trap, say, to the level 33 indicated in Fig. II; said valve 31 may be opened to drain it into the generator, where it belongs; said trap being designed to merely temporarily receive any

20 solvent water which would otherwise settle in the bottom of the refrigerating coil 23 and detract from the efficiency of the latter.

As shown in Fig. II, said rectifier 18 is merely a tubular conduit, containing baffle

25 plates 35, conveniently rigidly connected with an axial rod 36, forming a tortuous passage-

way for the refrigerant gas, in which entrained water is deposited from the ammonia gas. The condenser 20 is also a tubular

30 conduit which is coiled upon itself in the top of the cabinet 1 so as to occupy a minimum amount of space. Intermittent cooling of the residual solvent water in said generator 7 and condensation of the solvent water vapor and

35 ammonia gas, respectively in said rectifier 18 and condenser 20, are conveniently effected by respective streams of tap water supplied thru the pipe 38, which may be permanently connected with a house water

40 supply system. As best shown in Fig. I; the cooling water supply pipe 38 has the branch 39 provided with the control valve 40 which is automatically opened and closed, as hereinafter described. Said pipe 39 intermittently directs a stream of water thru the cooling coil 41 in the generator 7; from which coil the water is drained thru the waste pipe 42.

45 Said water supply pipe 38 has the branch 43 extending upwardly therefrom to the lower end of the condenser coil 20, thru which it extends, and down to the water jacket 45 which is in spaced relation with said rectifier 50 conduit 18 and forms the chamber 46, thru which the stream of cooling water flows and is discharged thru the waste pipe 47, which, conveniently, communicates with said waste pipe 42.

55 To pass air, and thus facilitate the free introduction and circulation of the cooling water; I find it convenient to provide the pipe 38 with the vent tube 48 which is open to the atmosphere at its top thru the cap 49; and to

60 provide the discharge pipe 47 with a similar vent tube 50 which is open to the atmosphere thru the cap 51.

As the operation of the refrigerating apparatus aforesaid is dependent upon the alternate heating of the generator 7 by the 70 flames 52 from the burner 12, say to 230° F., and an internal pressure of 160 pounds per square inch; and the cooling of the residual solvent water in said generator, say to 70° F., and an internal pressure of 20 pounds per 75 square inch, by the stream of tap water passing thru the coil 41; it is necessary to alternately open and close the gas valve 14 and the water valve 40, at predetermined temperatures of the contents of said generator and evaporator. Therefore, I find it convenient to employ separate bodies of thermic fluid, i. e., fluid having a high coefficient of expansion under increments of heat, for instance, alcohol, respectively located in the generator 80 7 and the evaporator manifold 22, and alternately operative, by their expansion, to serve as motors to actuate the controlling mechanism by which said gas valve 14 and cooling water valve 40 are alternately opened and 85 closed.

I inclose such a body of thermic motor fluid in the bulb 53 in the casing 54 which extends into said generator 7, and connect said bulb 53, by the tube 55, to the bellows 56, which is rigidly connected at its left hand end with the side wall of the control casing 57, as shown in Fig. I. The right hand end of said bellows is axially expanded to the right, as the motor fluid expands in said bulb 53, and axially contracted to the left, as said fluid contracts in said bulb 53, in accordance with fluctuations in the temperature of the refrigerant fluid contents of said generator 7. Such expansion of the bellows 56 is opposed by the spring 58 which is supported by the screw abutment 58' in engagement with the stationary lug 58" on said casing 57, as shown in Fig. II; so that the pressure and consequent temperature at which such expansion is 105 permitted may be adjustably determined.

Similarly, I inclose such a body of thermic fluid in the bulb 59 in the casing 60 extending into said manifold 22 and connect said bulb 59, by the tube 61, with the bellows 62 which is rigidly mounted at its right hand end in said control casing 57. The left hand end of said bellows 62 is axially expanded to the left, as the motor fluid expands in said bulb 59, and axially contracted to the right, as said fluid contracts in said bulb 59, in accordance with the fluctuations in the temperature of the refrigerant fluid contents of said condenser manifold 22.

The apparatus aforesaid is conveniently 125 calibrated to continually maintain a temperature below 45° F., in the refrigerator compartment 2, and the apparatus is shown in Fig. I in the condition and position of the parts when that temperature is reached. In 130

that condition, the thermic motor fluid in the bulb 59 has expanded to such an extent as to thrust said bellows 62 to the left, so as to swing the lever 64, (which is fulcrumed at 65 in said casing 57) against the stop 66 which is stationary in said casing. Said bellows 62 is opposed by the spring 68 which normally tends to thrust said lever 64 to the right, against the expansion of said bellows 62. The stress of said spring is adjustable by axial movement of its abutment 70, which has its stem 71 in screw threaded engagement with the nut 72 which is stationary in said casing 57. Said lever 64 has, pivotally connected with the lower end thereof at 74, the latch 75 which is adapted to slide back and forth thru the opening 76 in the valve lever 78 which is fulcrumed at 79 in said casing. As shown, said valves 14 and 40 are spaced apart, obliquely with reference to the axis of said fulcrum 79, being not only spaced longitudinally with respect to the conduit 13 for the fuel gas and the conduit 38 for the refrigerant cooling medium, which conduits support said valves in parallel relation, but also transversely with respect to said conduits, and have their respective valve stems 88 and 97 extending in parallel relation but similarly spaced apart obliquely with reference to the axis of the fulcrum 79 of said lever 78. As shown, said lever 78 includes three arms extending radially from its fulcrum, viz., a main vertical arm, which in its intermediate position is parallel with the valve stems 88 and 97, and two auxiliary arms, extending transversely to said main arm and in such obliquely spaced relation so as to register in cooperative relation with the respective valve stems 88 and 97, as shown. Said latch 75 has the shoulder 80 normally adapted to encounter the right hand side of said lever 78, so as to thrust the latter to the left, when said lever 64 is swung to the left by the expansion of said bellows 62. Said valve lever 78 has a pivotal connection at its upper end with the spring 81 which is compressed against the stationary pivot 82 at the top thereof, and the construction is such that the pressure of said spring 81 tends to thrust said valve lever 78 to the left or right, with a powerful snap action, if and when said lever 78 is pushed in either direction past the dead center line between said lever fulcrum 79 and said spring pivot 82. Therefore, it is only necessary for said latch shoulder 80 to be engaged with said lever 78 while the latter is being pushed toward the left past said dead center line and, immediately thereafter, said latch 75 rides upwardly upon the cone abutment 84 until said shoulder 80 is lifted above the bottom of the opening 76 in said lever 78, before the lever 64 encounters the stop 66. Said cone 84 has the stem 85 which is axially adjustable in the bearing 86 which is stationary in said control casing 57. Consequently,

altho the lever 78 is temporarily held in the position shown in Fig. I by the toggle spring 81; it is free to be pushed to the right, without interference of said latch.

In the position shown in Fig. I, said valve lever 78 has depressed the stem 88 of the valve 14 so as to open the latter and increase the volume of gas flowing to the burner 12 thru the conduit 13; a flame 52 being continuously maintained at said burner by a small quantity 73 of gas bypassed thru the casing of said valve 14.

The combustion of the augmented supply of gas to said burner 12 quickly raises the temperature of the refrigerant mixture contents of the generator 7 so as to generate ammonia gas from the refrigerant solution, which gas rises thru the rectifier 18 in which the small quantity of water vapor entrained in the gas is precipitated, and ultimately finds 83 its way back into said generator 7. The separated gas, practically free from water vapor, passes from said rectifier into the condenser 20 in which it is condensed and precipitated; so that the manifold 22 and coil 23 are thus 89 charged with substantially liquefied ammonia by the time the temperature of the mixture in the generator 7 has reached 230° F. By that time, the thermic fluid in the bulb 53, subjected to the temperature of the mixture 95 in said generator, has expanded and pushed the bellows 56 to the right so as to swing to the right the lever 91 which is fulcrumed at 92 in said control casing 57 and which is pivotally connected at 93 with the slide 94 which is mounted to reciprocate in said bearing 86, in opposition to said valve lever 78. Consequently, movement of said lever 91 and slide 94, to the right, pushes the valve lever 78 back, to the right, past its dead center line, 100 so that it is snapped to the right, by the toggle spring 81, to permit the valve 14 to be uplifted and closed by its spring 96. Such movement of the lever 78 contemporaneously depresses the stem 97 of the cooling water 110 valve 40 so as to open the latter and permit a stream of cooling water to flow from the supply pipe 38 thru the branch 39 and generator coil 41 and out the waste pipe 42, to thus quickly cool the residual solvent water 115 contents of the generator 7 from 230° F., and 160 pounds internal pressure to 70° F., and but 20 pounds pressure. Thereupon, the residual water in said generator is ready to reabsorb the ammonia gas previously generated 120 from it by the augmented heat from said burner 12. Such reabsorption is gradually effected as the initially condensed and liquefied refrigerant gas in the evaporator 23 is warmed by absorbing heat thru the brine tank 125 24 from the interior of the refrigerator food compartment 2. The evaporation and expansion of the refrigerant from the evaporator 23 may initially lower the temperature of said food compartment 2 below 40° F., and from 130

seven to twelve hours may elapse, in accordance with the outer atmospheric temperature to which the cabinet 1 is subjected, before the temperature of the interior of the food compartment 2 in said cabinet rises to 45° F. By that time, the major portion of the refrigerant with which the evaporator 23 was charged has found its way back into the generator and been absorbed by the cooled residual water therein. As above explained, as the temperature of the compartment 2 reaches 45° F., consequent expansion of the thermic fluid in the bulb 59 and bellows 62 operates to push the valve lever 78 to the left. Such movement releases the valve stem 97 and permits the valve 40 to be closed by its spring 98; contemporaneously with the opening of the gas valve 14. Of course, the cooling water then stagnant in the coil 41 in the generator 7 is heated, with the refrigerant contents of said generator, until the cooling water valve 40 is again opened, as above described, to recool the residual solvent water contents of said generator.

25 The safety gas valve 15 aforesaid is of substantially the same internal construction as the working gas valve 14 and is merely provided to comply with the requirements of the fire underwriters to entirely shut off the gas supply 15 thru the conduit 13, if and when the internal pressure in the refrigerant conduit 17 exceeds what is considered a safe limit. Said valve 15 has the stem 100 which is depressed to open it and is normally held depressed by the slide 101 which is mounted to reciprocate in the bearings 102 and 103 and is normally held in the position shown in Fig. I by the resilience of the flexible tube 105 which is appurtenant to the pressure gauge 106 which is connected with said refrigerant conduit 17 by the conduit 107 so as to manifest the internal pressure of the refrigerant. When that pressure exceeds the predetermined amount for which said safety device 40 is set; the bent tube 105 is flexed to the right, as indicated in Fig. IV, by the augmented pressure therein, so as to withdraw, to the right, said slide 101, which normally overhangs the top of the valve stem 100; so as to then permit said valve 15 to be closed by its spring 109. The arrangement is preferably such that it is necessary to manually open said valve 15 after it has been automatically shut; so as to insure that the abnormal condition incident to its closure is corrected, before it is opened.

20 The fusible plug 111 normally closes a safety vent, designed to relieve the unsafe internal pressure characteristic of such a temperature as would fuse the plug.

25 As above described, the single lever element 78 is operative as a toggle device by the pressure of the spring 81, to alternately open and close the fuel gas valve 14 and cooling water valve 40; the bodies of thermic

fluid in the bulbs 53 and 59 being alternately operative merely to push said toggle device to and fro past its dead center; the actual opening of the valves 14 and 40 being effected by the pressure of the spring 81, thus alternately rendered effective upon the stems 88 and 97 of said valves. As far as I am aware, it is broadly new to operate a valve by such a spring pressed toggle device and particularly to operate two valves in alternation, by the same spring. The thermostatic snap control disclosed herein is the subject matter of my copending divisional application Serial No. 380,517, filed July 24, 1929. Therefore, I do not desire to limit myself to the precise details of construction or arrangement of such a toggle device, nor to the specific construction and arrangement of the refrigerating system which I have chosen to illustrate the operation of my automatically operative valve controlling mechanism, as it is obvious that various modifications may be made therein, without departing from the essential features of my invention, as defined in the appended claims.

90 I claim:

1. In refrigerating apparatus, the combination with a generator wherein the refrigerant is periodically subjected to the action of heat from a gas burner, and to the action of a cooling medium; of conduits for fuel gas and for such cooling medium, disposed in parallel spaced relation; valves in the respective conduits spaced apart longitudinally with respect to said conduits, and having respective stems in parallel, spaced, relation; a lever fulcrumed between said stems and having a main arm extending from said fulcrum, substantially parallel with said stems, and auxiliary arms extending oppositely from said fulcrum, transversely to said main arm and respectively in cooperative relation with said stems; springs for the respective valves normally tending to close them in opposition to the auxiliary arms of said lever; and thermostatically operative means respectively adapted to alternately shift the main arm of said lever in opposite directions, and thereby alternately open said valves and permit them to be closed in accordance with the temperature in respectively different regions of the refrigerating apparatus.

2. In refrigerating apparatus, the combination with a generator wherein the refrigerant is periodically subjected to the action of heat from a gas burner and to the action of a cooling medium; of conduits for fuel gas and for such cooling medium; valves in the respective conduits having respective stems in parallel, spaced, relation; a lever fulcrumed between said stems, on an axis transverse to said stems and having a main arm, and auxiliary arms extending radially from said fulcrum in different directions, said auxiliary arms being respectively in coopera-

tive relation with said stems; and thermostatically operative means respectively adapted to alternately shift the main arm of said lever in opposite directions, and thereby alternately open said valves and permit them 5 to be closed in accordance with the temperature in respectively different regions of the refrigerating apparatus.

In testimony whereof, I have hereunto signed my name at Conshohocken, Pennsylvania, this eleventh day of October, 1928.

JOSEPH WILLIAM WINTER.
